US00D667785S

(12) **United States Design Patent**
Ueda et al.

(10) **Patent No.:** US D667,785 S
(45) **Date of Patent:** ** Sep. 25, 2012

(54) **BATTERY CHARGER**

(75) Inventors: **Arinobu Ueda**, Tokyo (JP); **Yozo Matsuzaka**, Tokyo (JP); **Osamu Miki**, Tokyo (JP)

(73) Assignee: **Sony Corporation**, Tokyo (JP)

(**) Term: **14 Years**

(21) Appl. No.: **29/371,633**

(22) Filed: **Jun. 13, 2011**

Related U.S. Application Data

(63) Continuation-in-part of application No. 29/309,326, filed on Jul. 25, 2008, now Pat. No. Des. 639,732.

(57) **CLAIM**

The ornamental design for a battery charger, as shown and described.

DESCRIPTION

FIG. 1 is a perspective view of a first embodiment of a battery charger showing our new design;

FIG. 2 is a front elevational view thereof;

FIG. 3 is a left side elevational view thereof; and

FIG. 4 is a right side elevational view thereof.

FIG. 5 is a perspective view of a second embodiment of a battery charger showing our new design;

FIG. 6 is a front elevational view thereof;

FIG. 7 is a left side elevational view thereof; and,

FIG. 8 is a right side elevational view thereof.
